(57) **CLAIM**

The ornamental design for an oral-motor chew tool, substantially as shown and described.

DESCRIPTION

FIG. 1 is a left, front perspective view of an oral-motor chew tool, showing my new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The areas inside the broken lines form no part of the claimed design.
